UNITED STATES PATENT OFFICE

ALFONS WAGNER, OF DUISBURG, AND EDUARD POHL, OF RHONDORF-ON-THE-RHINE, GERMANY, ASSIGNORS TO GUTEHOFFNUNGSHÜTTE OBERHAUSEN AKTIENGESELLSCHAFT, OF OBERHAUSEN, GERMANY, A CORPORATION OF GERMANY

METHOD OF BLOWING BLAST INTO SHAFT FURNACES

Application filed July 11, 1927, Serial No. 204,929, and in Germany October 15, 1926.

In shaft furnaces, hitherto, the blast is blown into the shaft through tuyères in such a way that it exerts a vigorous suction (that is—aspirating or injector) effect on the furnace gases at about the whole length of its jet that is directed at right angles to the vertical axis of the furnace shaft, whereby in the latter an oxidizing zone is created which extends from the mouth of the tuyère 5 toward the middle of the furnace shaft in about elliptical formation and acts detrimentally upon the working of the shaft furnace while it requires an excessive consumption of coke.

15 The present invention relates to an improved method, and an improved construction of tuyères for putting the same into practice, of decreasing the noxious effect of said oxidizing zone by reducing the kinetic 20 energy of the blast and changing it partly to pressure whereby the incoming blast is diverged and the oxidizing zone is displaced from its noxious position mentioned to a practically neutral position extending in up 25 and downward directions from the mouth of the tuyère along the inner walls of the furnace shaft. To this end, according to the invention, the inner bore of the tuyère is tapered from the mouth of the tuyère toward 30 the rear inlet end thereof, which taper extends either at a short distance from the mouth only, or over part of the length of the tuyère, or over its whole length.

In the accompanying drawings:

35 Figure 1 shows in longitudinal section a tuyère of conventional type showing schematically the conventional shape and chemical composition of the blast stream emitted by said tuyère;

40 Figure 1A is a sectional view, on an enlarged scale, taken along the plane indicated by the arrows 1A—1A of Figure 1, indicating the bulbous nature of the blast emitted by the tuyère shown in Figure 1;

45 Figure 1B is a sectional view, on an enlarged scale, taken along the plane indicated by the arrows 1B—1B of Figure 1;

Figure 2 shows in longitudinal section a 50 tuyère embodying the principles of the pres-

ent invention, indicating schematically the blast stream emitted by said tuyère;

Figure 2A is a sectional view taken along the plane indicated by the arrows 2A—2A of Figure 2; and

55 Figures 3, 4 and 5 illustrate other forms blast stream emitted by said tuyère; present invention.

The numeral 1 indicates a tuyère of conventional type mounted in the wall 2 of a 60 shaft furnace and projecting beyond the lining of said wall. The numeral 3 indicates schematically the typical blast stream emitted by said tuyère 1. It will be noted that the blast 3 comprises a central core 3a of air, 65 indicated by the characters $O_2—O_2$, indicating oxygen.

Inasmuch as said tuyère has a continuously 70 converging wall, the blast stream 3 enters the furnace with suction effect (that is, the well known aspirating or injector effect characterized particularly by the constricted throat of the blast stream 3b), whereby the surrounding furnace gases, consisting largely of carbon monoxide CO , are strongly induced to flow into and mingle with the blast stream. The movement of furnace gases is indicated by the curved arrows. The deleterious effects of this action are two-fold.

75 First, there is a mechanical action by the induced gas flow upon the adjacent wall of the furnace which is destructive; and, second, carbon monoxide gas combines with the air or oxygen in the blast 3, forming a

80 layer 3c of carbon dioxide CO_2 , which is, in a blast furnace, an oxidizing gas. The numerals 3d and 3e indicate particles of coke and iron, respectively, coming in contact with the oxidizing layer 3c, resulting in the uneconomical consumption of said particles

85 of coke and the oxidation of said particles of iron. Due to the relatively high kinetic energy of the gas produced by the conventional type of tuyère shown in Figure 1, said blast is elongated a relatively great distance

90 toward the axis of the furnace, establishing an extensive oxidizing zone having a decidedly deleterious effect upon the coke consumption and in iron oxidation.

95 In the construction shown in Fig. 2, the

inner bore of the tuyère 4 is tapered at 5 from the mouth of the tuyère toward the rear end thereof, said taper extending at a short distance from the mouth only; the oxidizing zone 6 being thereby displaced in up and downward directions from the mouth of the tuyère.

In the construction shown in Fig. 3, the taper 8 of the inner bore of the tuyère 7 extends from the mouth toward the rear end of the latter over the whole length thereof, the oxidizing zone 9 being thereby also displaced in up and downward directions from the mouth of the tuyère.

In the preferred construction shown in Fig. 4, the taper 11 of the inner bore of the tuyère 10 extends from the mouth toward the rear end of the latter over part of the length thereof, the oxidizing zone 12 being thereby also displaced in up and downward directions from the mouth of the tuyère along the inner walls of the furnace shaft 13.

In the construction shown in Fig. 5, a separate blast nozzle 14 extends through the rear inlet end of the tuyère 15, of which the inner bore is tapered at 16 over its whole length, to about the middle thereof and has perforations 17 distributed over its circumference and located at a distance from its mouth; the improved action mentioned of displacing the oxidizing zone in front of the tuyère mouth being thereby further increased, as the incoming blast is throttled by said perforations and further by the taper 16.

Preferably, the inner bore of the improved tuyère directly at the mouth thereof may be rounded in funnel-shaped fashion as indicated at 18 in Fig. 5, whereby the diverging action upon the incoming blast is further increased.

The underlying principles of the present invention will be clear from a discussion of the method as carried out in connection with the tuyère illustrated in Figure 2. Referring to said figure, it will be noted that the blast stream issuing from the tapered portion 5 of the tuyère 4 increases progressively in diameter from the tuyère mouth, whereby the injector action upon the carbon monoxide gas within the furnace is minimized. Moreover, due to the fact that the blast is flared in all directions transversely of the axis of the tuyère, the distance to which said blast is projected into the furnace is minimized.

According to the disclosure in Figure 2, the injector action on the surrounding furnace gases consisting largely of carbon monoxide CO is substantially eliminated. Due, however, to the presence of particles 3d of carbon in the form of coke, the inner core of oxygen O₂ is converted to an envelope of CO₂, which, as stated above, is, in a blast furnace, an oxidizing gas; and further into CO. However, due to the fact that the core of air O₂ is much shorter in the structure disclosed in Figure 2.

than is the core of air O₂ in the conventional structure shown in Figure 1, the oxidizing envelope CO₂ is more quickly reconverted to CO in the disclosure of Figure 2 than is the case in the disclosure of Figure 1. The method of distributing the air as disclosed in Figure 2 therefore materially reduces the oxidizing zone from that produced in the mouth as illustrated in Figure 1.

As indicated above, the method as produced by the structure shown in Figures 3, 4 and 5 will be clear from that discussed in connection with Figure 2.

What we claim, is:—

1. In the operation of blast furnaces, the improvement which consists in conducting the air blast in a converging funnel-shaped formation and thereafter in a flaring funnel-shaped formation into the furnace gas without injector effect and thereby diminishing the premature burning of the furnace gases and fuel as well as diminishing the dimension of the oxidizing zone in its longitudinal axis in the tuyère plane of the furnace.

2. The improvement described in claim 1, in which the air blast is introduced into the furnace with its kinetic energy partially converted into energy or pressure.

In testimony whereof we have hereunto set our hands.

ALFONS WAGNER.
EDUARD POHL.

CERTIFICATE OF CORRECTION.

Patent No. 1,830,683.

Granted November 3, 1931, to

ALFONS WAGNER and EDUARD POHL.

It is hereby certified that error appears in the printed specification of the above numbered patent requiring correction as follows: Page 1, line 57, strike out the words and semi-colon "blast stream emitted by said tuyere;" and insert instead of tuyere embodying the principles of the; page 2, line 93, claim 2, for "or" read of; and that the said Letters Patent should be read with these corrections therein that the same may conform to the record of the case in the Patent Office.

Signed and sealed this 9th day of February, A. D. 1932.
